MECHANICAL TIME FUSE

Maurice P. Whitney, Elmira, N. Y., assignor to
 Bendix Aviation Corporation, South Bend, Ind.,
 a corporation of Delaware

Application April 1, 1943, Serial No. 481,455

1 Claim. (Cl. 102—71)

1

The present invention relates to a combined point detonating and mechanical time fuse for explosive projectiles and more particularly projectiles to be discharged from rifled cannon.

For certain types of artillery service, it is desirable to control the detonation of projectiles by a timing device, and to also provide for detonation by impact on the target irrespective of the elapsed time interval.

Various methods have been proposed for securing the desired results, but the structure heretofore disclosed has in general been subject to the disadvantages that the time control had to be considerably modified to incorporate the contact detonator, and the attendant complication has tended to reduce the efficiency of each of the component controlling devices.

It is an object of the present invention to provide a novel contact and time controlled fuse which is efficient and reliable in operation and simple in construction.

It is another object to provide such a device in which the incorporation of the contact detonator involves no modification of the operating mechanism of the time control.

It is another object to provide such a device in which there is a minimum of time lag between the actuation of the contact fuse and the ignition of the base charge of the projectile.

Further objects and advantages will be apparent from the following description taken in connection with the accompanying drawing in which:

Fig. 1 is a vertical substantially mid-sectional view of the nose of a shell showing a preferred embodiment of the invention and;

Fig. 2 is a section taken substantially on the line 2—2 of Fig. 1.

In Fig. 1 there is illustrated the upper portion of a shell 1 of conventional form containing a base charge 2 and having a threaded opening for receiving a closure plug and adapter 3 which serves to confine the base charge in the shell and is internally threaded to provide a seat for the base 4 of a timer mechanism for controlling the ignition of the charge 2.

The base 4 of the fuse is formed with a cylindrical socket 5 in which a clock-work timing mechanism indicated generally by the numeral 6 is seated. Means for retaining the timing mechanism in its seat is provided in the form of a cup-shaped member 7, having an out-turned flange 8 at its lower end which is pressed against the bottom of the socket 5 by suitable means such as a threaded lock ring 9.

2

The timing mechanism may be of any conventional form such, for instance, as the type illustrated in the patent to Junghans, Number 1,693,516, and has at its upper end a skeleton timing disk 11 adapted to be rotated by the gearing of the clock-work in order to control the detonation of the shell.

The lower end of the base 4 of the fuse is provided with a chamber 12 in which is mounted an annular powder bag 13 which is retained by a plug 14 threaded in said base and provided with a passage 15 adapted to connect with a passage 16 through the adapter 3 which communicates with the interior of the shell holding the base charge 2.

According to the present invention a contact detonating mechanism is placed in the nose of the fuse and is arranged to cause the shell to explode upon impact of the fuse with a target. As here shown this mechanism comprises a firing pin 17 slidably mounted in a bearing member 18 in position to strike a cap 19 of suitable fulminating material, carried in a threaded bushing 21. Primary explosive charge 22 is mounted in the nose of the fuse beneath the cap 19 and directly above the retainer 1 of the timing mechanism which is provided with an opening 24 permitting the flame from the primary charge 22 to penetrate the time fuse mechanism. An explosive pellet 23 is mounted in the bushing 21 adjacent the cap 19 so as to be exploded by the cap to thereby ignite the charge 22.

In order to permit the flame from the charge 22 to reach the powder bag 13, the top plate 35 of the casing for timing mechanism 6 is provided with apertures 30, and said casing has axially extending channels 25 so formed therein as to register with passages 26 provided in the base 4 of the fuse to connect the socket 5 thereof with the powder bag chamber 12.

In order to prevent premature or undesired actuation of firing pin 17, locking means therefore is provided in the form of a pair of latch members 27, 28 which normally engage beneath a shoulder 29 of the firing pin to prevent its being projected into engagement with the cap 19. The latch members 27, 28 are yieldably held in normal position by suitable means such as a spring 31, but are movable by centrifugal force radially outward so as to free the firing pin and thereby arm the fuse.

The fuse is enclosed by a casing member 32 of the usual ogive form which is retained on the fuse by any suitable means such as by tongues 33 pressed inwardly to engage beneath a flange

member 34 fixed to the retainer 7. The casing is rotatable to effect the adjustment of the timing mechanism in the conventional way. Since the timing mechanism forms no part of the present invention, no further description thereof is deemed necessary.

In operation the timing mechanism is set to explode the shell at a predetermined time interval in the usual manner in accordance with the estimated range of the target, the shell being at this time safe to handle by reason of the fact that the firing pin 17 is prevented from engaging the cap 19 by the locking members 27, 28. When the shell is discharged from a rifled gun, the rotation of the shell caused by the rifling causes the members 27, 28 to move radially thus releasing the firing pin 17 and rendering the fuse sensitive to impact.

If the timing mechanism is so set as to be operative prior to impact on the target, the shell will be exploded thereby after the predetermined time interval has elapsed. However, if the shell contacts the target earlier than expected, the impact against the target will cause the firing pin 17 to engage and fire the cap 19 which in turn ignites the primary charge 22. Flame from the charge traverses the opening 24 of the retainer 7, passes through the openings in the timing disk 11 into the passages 25, and through the passages 26 into the powder bag chamber 12, thus igniting the powder bag 13, the flame from which passes through the opening 16 into the base charge chamber and ignites the charge 2.

It will be seen that the two detonating devices operate independently and without requiring modification of their operating mechanism in order to accomplish the dual form of control. Moreover since the connection from the contact fuse to the powder bag 13 is accomplished by means of flame propagation rather than by any mechanical device involving inertia, there is a minimum of time lag between the actuation of the contact control and the ignition of the base charge.

Although but one embodiment of the invention has been shown and described in detail, it will

be understood that other embodiments are possible and various changes may be made in the form and arrangement of the parts without departing from the spirit of the invention as defined in the claims appended hereto.

What is claimed is:

In an explosive projectile for rifled cannon, a compound fuse comprising a base having a cylindrical socket, a time control mechanism seated in the socket comprising a cylindrical casing, operating gearing mounted therein and a perforated timing disc outside of the casing, a cup-shaped retainer enclosing the time control mechanism and holding it in the socket, said retainer having an opening above the disc, a contact igniting device including a primary charge mounted in the fuse above the time control mechanism, and a secondary charge for igniting the base charge of the projectile in said base beneath the socket; said cylindrical casing having axially arranged exterior channels communicating with the space beneath the timing disc, and the base having openings registering with the channels thereby completing passages for conducting the flame from the primary charge through the openings in the retainer and timing disc to the secondary charge.
